REFRIGERATING APPARATUS

Paul E. Kronenberger, Dayton, Ohio, assignor to General Motors Corporation, Detroit, Mich., a corporation of Delaware

Filed July 10, 1964, Ser. No. 381,666
5 Claims. (Cl. 312—236)

This invention pertains to refrigerating apparatus and more particularly to a shelving and support arrangement for drawer type receptacles within a refrigerator.

It is customary in recent years to provide a single shelf at the bottom of the food compartment of refrigerators for supporting several receptacles for fresh vegetables and/or keeping meats such as is shown in Patent No. 2,960,849 issued November 22, 1960. However, such a large shelf, because of its size, is cumbersome and difficult to remove, clean and replace.

It is an object of this invention to provide an arrangement in which such shelf is divided into sections in such a way that these sections are held tightly together so that they appear to be one and yet be easy to remove, clean and replace.

It is another object of this invention to provide an arrangement in which such a shelf is divided in sections and in which the means are provided for controlling the air circulation in such a way that the receptacle beneath one shelf section is kept cooler than the receptacle beneath the other shelf section.

It is another object of this invention to provide an arrangement in which such shelving is divided into sections in such a way that sections are held tightly together and provided with improved, simple supporting arrangements which will hold the sections firmly in place and yet permit ready removal, cleaning and replacement.

These and other objects are attained in the form shown in the drawings in which two plastic shelf sections have flanges on their side edges provided with drawer guides. At their meeting edges, one of the shelf sections is provided with an offset flange on which the inset flange of the other shelf section is supported. These are interlocked together by upstanding projections on the offset flange extending through apertures in the inset flange of the other shelf section. The adjacent flanged edges beneath the drawer guides are provided with downwardly extending ribs which fit into grooves in a vertical partition wall having an elongated notch beneath providing for restricted air circulation from one side to the other. Cold air is fed in beneath the shelf above one of the receptacles for circulation through the receptacle and out apertures in the side wall thereof as well as apertures in the flange on the outer edge of one of the shelves for circulation around the one receptacle to keep it cold while the restricted circulation permitted beneath and in front of the partition to the other receptacle which keeps the other receptacle refrigerated at a substantially higher temperature.

Each of the outer side flanges have a projection with a rearwardly opening notch fitting onto a shelf peg extending inwardly from the adjacent side wall. The rear flanges of each of the shelf sections are provided with a horizontally elongated aperture adjacent the meeting edges which is supported upon a pin projecting forwardly

2

from the rear wall of the cabinet. The outer side flanges of the shelves adjacent the front also have downwardly extending projections containing notches which are likewise supported upon shelf pegs extending inwardly from the side walls. The one shelf section is also provided with a supporting post located in front of the partition wall and having rearwardly extending vertical ribs or projections extending on opposite sides of the partition wall to prevent its lateral movement.

10 Further objects and advantages of the present invention will be apparent from the following description, reference being had to the accompanying drawings wherein a preferred embodiment of the present invention is clearly shown.

15 In the drawings:

FIG. 1 is a front vertical sectional view of a dual shelf and receptacle supporting arrangement embodying one form of my invention taken along the line 1—1 of FIG. 2;

19 FIG. 2 is a side vertical sectional view taken along the line 2—2 of FIG. 1;

FIG. 3 is a second side sectional view taken along the line 3—3 of FIG. 1 through the second receptacle;

23 FIG. 4 is a fragmentary enlarged sectional view showing the meeting flanged and interlocked edges of the shelf sections and the adjacent portions of the partition walls and the receptacles taken along the line 4—4 of FIG. 2;

27 FIG. 5 is a fragmentary sectional view taken along the line 5—5 of FIG. 4.

29 Referring now to the drawings and more particularly to FIGS. 1 to 3, there is shown the bottom portion of a refrigerated food compartment 20 having side walls 22, a rear wall 24 and a bottom wall 26. The compartment 20 is closed by a conventional refrigerator door 80. According to my invention, the shelf at the bottom of the compartment 20 is formed of a suitable plastic and divided into a right section 28 and a left section 30, each generally rectangular in shape and each provided with flanges on their four edges.

33 The right shelf section 28 is provided with a rear flange 32 containing a horizontally elongated aperture 34 fitting over the pin 36 projecting forwardly from the rear wall adjacent the offset flange 38 at the central edge of the section 28. The flange 38 is provided with a guideway 40 which on its upper face has two upwardly extending projections 42. The flange 44 on the opposite outer side is provided with a similar guideway 46 also providing an offset flange. This flange is also provided at the rear with a projection 48 extending sidewardly and provided with a rearwardly opening notch 50 which receives a shelf projection or pin 52 extending outwardly from the side wall 22. The flange 44 at the front is provided with a second outwardly extending projection 54 provided with a downwardly opening notch 56 receiving a pin or shelf peg 58 extending outwardly from the side wall 22. The shelf section 28 therefore can be readily inserted by first moving its rear edge rearwardly so that the pin 36 registers with the opening 34 and the pin or shelf peg 52 registers with the notch 50 after which the front can be moved downwardly with the notch 56 upon the shelf peg or pin 58. The shelf section 30 can be inserted in a similar manner. Both can be removed separated by reversing the procedure.

The flange 38 below the guideway 40 is provided with a downwardly extending rib 60 which extends into a groove 62 in a vertical partition wall 64 which extends substantially from the rear wall 24 forwardly to a supporting post 66 extending downwardly from the front left corner of the shelf section 28 to the breaker strip 68 at the front of the bottom wall 26. This post 66 has on its opposite sides a rearwardly extending projection 70 extending on each side of the front edge of the partition wall 64 so as to hold the wall 64 vertically at all times. This partition wall 64 also has a front portion 72 resting upon a breaker strip and a rear portion 74 resting upon the bottom wall 26. In between there is an elongated slot 76 which allows a limited evenly distributed amount of air flow from beneath the section 28 to the space beneath the section 30. A space 78 is also provided at the rear for an additional amount of air flow around the compartment. In addition air can pass around the front of the post 70 and between the post 70 and the adjacent surface 80 of the door.

Adjacent the section 28, the section 30 has an inwardly flanged edge 82 adapted to rest on the outwardly extending offset flange 38 of the section 28 and having apertures 84 which receive the projections 42 extending upwardly from the offset flange 38 to complete the interfitting of the adjacent edges of the sections 28 and 30 so that they appear to be substantially as one shelf when in place. The inwardly offset flange 82 is provided with a guideway 86 beneath which is a downwardly projecting rib 88 extending into a second groove 90 in the top of the partition wall 64 which is parallel and along one side of the groove 62. The sections 28 and 30 have their downwardly extending projecting ribs 60 and 88 separated by the upwardly extending tongues 92 between the grooves 62 and 90 in the top of the partition wall 64 as particularly shown in FIG. 4. The shelf section 30 also has a rear flange 94 provided with a horizontally elongated aperture 96 fitting over the pin 98 extending forwardly from the rear wall 24. The section 30 also has a left side flange 121 including the guideway 123 and has a projection 125 with a downwardly extending notch fitting over the shelf peg 127 adjacent the front on the same line as the shelf peg 58. The sections 28 and 30 are provided with matching front ornamental flanges 129. They are also provided with a series of transverse strengthening ribs 130 as shown in FIGS. 1 and 3.

The guideways 40 and 46 support a removable drawer type receptacle 131 which has outwardly extending flanges 133 slidably mounted in the guideways 40 and 46 as shown in FIG. 1. Beneath the shelf section 30 is a second receptacle 135 similar to the receptacle 131 but preferably wider. It is likewise provided with outwardly extending flanges 137 which are slidably mounted in the guideways 86 and 123. Each of the receptacles 131 and 135 is provided with an ornamental handle 139 of the type shown in FIG. 3.

The receptacle 131, which is intended primarily for fresh meat storage, is maintained at a cooler temperature than the receptacle 135 which is intended for fresh vegetables. To accomplish this, the rear wall 24 is provided with a cold air intake 141 which discharges cold air forwardly through a registering opening 143 in the flange 32 which discharges the air between the shelf section 28 and the receptacle 131. Some of this air flows into the receptacle 131 and out through the pairs of apertures 145 provided at the front and rear of the side walls. The front part of the flange 44 is provided with a pair of apertures 147 through which additional cold air can escape. This cold air then circulates completely around the outside of the receptacle and thence either passes between the post 66 and the door 80 to the left side of the partition 64 or passes through the space or slots 76 beneath the partition 64 so that a substantially evenly distributed flow of air is maintained from one side of the partition wall 64 to the other. This air then flows around the receptacle 75

135 to cool its contents to a desirable temperature. Preferably the flow of air is such as to maintain the receptacle 131 at about 30° F. and the receptacle 135 at about 34° F.

5 The rear flange 94 may be provided with a strip 149 of elastomeric material on its front face so that the rear flange 151 of the receptacle 135 can be sealed against it. The front flange 129 of the section 30 is provided with a downwardly extending rib 152 which has provided on its lower edge a gasket type seal 153. The receptacle 135 by the contact of its side flanges 137 with the guideways 123 and 86 and by the sealing contact of its rear flange 151 with the elastomeric strip 149 and by the sealing contact of the rear face of its handle 139 with the sealing gasket 153 is provided with a sealing arrangement which substantially prevents the circulation of air within the receptacle 135 so that dehydration of the fresh vegetables is minimized.

10 While the embodiment of the present invention as herein disclosed, constitutes a preferred form, it is to be understood that other forms might be adopted.

20 What is claimed is as follows:

1. A refrigerator including side and rear and bottom walls for a compartment to be cooled, an upwardly extending partition wall extending upwardly from said bottom wall and having a plurality of recesses, a first shelf section extending to one side of said partition wall having a projection fitted into one of said recesses to provide an interfitting connection with said partition wall, a second shelf section separate from the first shelf section and having a projection fitted into one of said recesses in said partition wall, said second shelf section also having means interfitting with said first shelf section.

2. A refrigerator including side and rear and bottom walls for a compartment to be cooled, an upwardly extending partition wall extending upwardly from said bottom wall and having a plurality of recesses, a first shelf section extending to one side of said partition wall having a projection fitted into one of said recesses to provide an interfitting connection with said partition wall, a second shelf section separate from the first shelf section and having a projection fitted into one of said recesses in said partition wall, said second shelf section also having means interfitting with said first shelf section, each of the edge portions of each of said shelf portions being provided with guideways, and a drawer type receptacle slidably mounted on each set of guideways beneath each shelf section.

3. A refrigerator including side and rear and bottom walls for a compartment to be cooled, an upwardly extending partition wall extending upwardly from said bottom wall, a first shelf section extending to one side of said partition wall having an interfitting connection with said partition wall, a second shelf section separate from the first shelf section but meeting with the adjacent portion of the first shelf section and interfitting with both said first shelf section and said partition wall, each of the edge portions of each of said shelf portions being provided with guideways, and a drawer type receptacle slidably mounted on each set of guideways beneath each shelf section, means for discharging cold air between one of said receptacles and the shelf section above it, said partition wall having a raised bottom edge portion to provide for a restricted air flow from one side of said partition wall to the other to make more uniform the cooling of the other receptacle.

4. A refrigerator including side and rear and bottom walls for a compartment to be cooled, an upwardly extending partition wall extending upwardly from said bottom wall, a first shelf section extending to one side of said partition wall having an interfitting connection with said partition wall, a second shelf section separate from the first shelf section but meeting with the adjacent portion of the first shelf section and interfitting with both said first shelf section and said partition wall, one of said shelf sections being provided with a post in front of said partition wall extending downwardly to said bottom wall, said

post having rearwardly extending projections extending on opposite sides of said partition wall for limiting lateral movement of said partition wall.

5. A refrigerator including side and rear and bottom walls for a compartment to be cooled, an upwardly extending partition wall extending upwardly from said bottom wall, a first shelf section extending to one side of said partition wall having an interfitting connection with said partition wall, a second shelf section separate from the first shelf section but meeting with the adjacent portion of the first shelf section and interfitting with both said first shelf section and said partition wall, each of the edge portions of each of said shelf portions being provided with guideways, and a drawer type receptacle slidably mounted on each set of guideways beneath each shelf section, each of said shelf sections having a flange adjacent said side walls extending to the adjacent guideway, means

for discharging air between one of said receptacles and the shelf section above it, the front portion of the flange nearest said one receptacle being provided with an outlet opening between the adjacent guideway and the top of said shelf.
